FOREIGN PATENT DOCUMENTS

WO 2012135075 A1 10/2012

Primary Examiner — Cynthia R Underwood(74) *Attorney, Agent, or Firm* — ASLAN LAW, P.C.(57) **CLAIM**

The ornamental design for a cord holder, as shown and described.

DESCRIPTION

FIG. 1 is a front elevational view of a cord holder showing my new design.

FIG. 2 is a rear elevational view thereof.

FIG. 3 is right side view thereof.

FIG. 4 is a left side view thereof.

FIG. 5 is a top plan view and a bottom plan view thereof.

FIG. 6 is a perspective view thereof from the front and right sides.

FIG. 7 is a perspective view thereof from the front and top sides.

FIG. 8 is a perspective view thereof from the front, top, and right side.

FIG. 9 is a perspective view thereof from the front, top, and left side; and,

FIG. 10 is a perspective view thereof from the rear, top, and left side.

The broken lines are included for the purpose of illustrating unclaimed portions of the design and form no part thereof.

1 Claim, 10 Drawing Sheets---
